MACHINE FOR OPERATING UPON
SHEET MATERIAL

Robert N. Sandberg, Beverly, Mass., assignor to
United Shoe Machinery Corporation, Paterson, N. J., a corporation of New Jersey

Application March 23, 1934, Serial No. 717,053

9 Claims. (Cl. 164—58)

This invention relates to machines for operating upon sheet material and is herein illustrated as embodied in a clicking machine.

Clicking machines as heretofore constructed commonly comprise a bed, a cutting block supported upon the bed, and a presser member arranged for reciprocation relatively to the bed, thereby forcing a freely movable die through sheet material, such as leather, positioned upon the cutting block. Cutting blocks used in such machines are subject to wear and frequently must be removed from the machine for resurfacing operations or for replacement. Consequently it is customary to secure a cutting block in position upon the bed of the machine by devices such as clamping bolts which can be released when it is necessary to remove the block.

It is an object of the present invention to provide, in a machine of the type referred to, a block-securing device of novel construction which will be especially adapted to facilitate the assembly or disassembly of a cutting block and the bed of the machine.

To this end and as illustrated, the invention provides a bed, a cutting block supported upon the bed and a clamping device comprising a toggle mechanism for securing the block to the bed. By the use of the toggle mechanism in the construction set forth, it is possible quickly to secure the block to the bed or to release it from the bed thus to save the time which an operator would otherwise have to spend in loosening or tightening the attaching bolts commonly used heretofore.

Other features of the invention will be apparent from the following detailed description when taken in connection with the accompanying drawings and will be pointed out in the claims.

In the drawings,

Fig. 1 is a side view partly in section of a portion of a clicking machine disclosing one form of block-securing device;

Fig. 2 is a plan view showing the cutting block in position upon the bed of the machine;

Fig. 3 is a detailed view partly in section of the toggle mechanism for operating the clamping device;

Fig. 4 is a side elevation of a part of a clicking machine illustrating a modified form of block-securing device; and

Fig. 5 is a plan view of a portion of the machine equipped as in Fig. 4 and illustrating also a work table mounted adjacent to the cutting block of the machine.

The clicking machine illustrated in Figs. 1

and 2 comprises a frame 10, carrying a flat bed 12 upon which is positioned a cutting block 14, and a presser arm 16 which is arranged for reciprocation relatively to the bed by means of mechanism not shown.

The cutting block 14 is square in cross section as shown in Fig. 2 and is particularly adapted, as is the entire machine shown, for use in operating upon small work such as appliques or other small blanks which go into the making of the uppers of shoes. Preferably, the cutting block 14 is of wood and is composed of separate blocks or sections 17 glued together and secured in position against forces applied to the upper surface of the block by clamping irons or bolts 18 which extend along the sides of the block and are secured together at their ends by nuts 20. Additional reinforcement of the block is obtained by rods 22 and 24 which extend through the block and connect the irons 18 at opposite sides thereof. The rod 22 is positioned in a groove 26 extending along the lower surface of the block, the rod having reduced ends 28 which pass through opposite clamping irons 18 and are secured in position by nuts 30. The reinforcing rod 22 extends at right angles to the rod 24 and passing through two of the clamping irons 18 and through a slot 32 in the rod 22. This arrangement of clamping irons 18 and reinforcing rods 22 and 24 produces a rigid block structure 30 which can effectively withstand blows applied to the upper surface of the cutting block 14.

In order to secure the cutting block to the bed 12 there is provided quickly detachable clamping means which will now be described. Secured to the central portion of the rod 22 is a spindle or shank 34 which extends downwardly through a clearance opening 36 and a bore 38 in a boss 40 on the under side of the bed 12. The shank 34 is arranged to be forced in a downward direction by means of a toggle lever 42 having ears 43 mounted upon a pin 44 carried by the boss 40 and is operatively connected to a sleeve 46 slidably mounted upon the shank 34 by toggle links 48 mounted upon pins 50, carried by the lever, and connected to the sleeve 46 by pins 52. The lower end of the shank 34 is screw-threaded and carries a nut 54, held in adjusted position by a nut 55, which serves to limit downward movement of the sleeve 46 upon the shank, the sleeve 50 being normally forced upwardly by springs 56 extending between the pins 44 and 52. Upon rotation of the lever 42 in a counterclockwise direction (Fig. 1) the toggle links 48 are brought into a position with their axes in line with the pins 55

44 and 50, thus forcing the sleeve 46 downwardly causing it to engage the nut 54 thereby to force the shank 34 downwardly with sufficient pressure to clamp the cutting block 14 to the bed 12. The 5 clamping device can readily be released by moving the lever in a clockwise direction thereby to break the toggle.

One advantage of the construction just described is that the positioning of the cutting 10 block upon its supporting bed is facilitated as in cases where it is desired to locate a new block surface at the point where the operator does most of the work, that is, the front of the machine. This can be done readily merely by releasing the toggle, rotating the block on the bed about the shank 34 through 90° and then operating the toggle lever 42 again to clamp the block to the bed. By thus shifting the position of the 15 block upon the bed at frequent intervals the wear 20 upon the block is evenly distributed thus rendering frequent resurfacing unnecessary.

In Figs. 4 and 5 I have shown in a modified form a block-securing device in which there are several toggle-operated clamps positioned along 25 the sides of a cutting block. In this instance, the machine comprises a frame 60 having a bed 62 supporting a cutting block 64 and having a presser member 66 arranged for reciprocation 30 relatively to the bed by mechanism not shown. The block is arranged to be secured to the cutting bed by a plurality of clamping bolts 68, each of which has a hooked portion 70 adapted to enter a slot 72 in one of the block clamping irons 14. Each of the clamping bolts is carried by a 35 toggle block 76 mounted upon a pin 78 carried by a bifurcated toggle lever 80 which in turn is carried by a pin 82 mounted in ears 84 on the bed of the machine. Within the toggle block 76 is positioned a nut 86 adapted to receive the 40 screw-threaded end 88 of the clamping bolt 68, the nut 86 being held against rotation in the block by means of a pin 90 which is adapted to engage a flat side 92 of the nut. The nut 86 is provided with an upwardly extending reduced 45 portion or sleeve 94 which carries a stiff spring 96 the upper end of which bears against a shoulder 98 on the toggle block 76. This spring constitutes a yieldable connection between the bolt 68 and the toggle block 76 by which pressure 50 can be applied to the bolt.

In the use of the clamping bolts 68 a bolt is 55 swung about the pivot pins 78 and 82 until the hooked portion 70 of the bolt engages the bottom of a slot 72 and the toggle lever 80 is then forced down until the pivot pin 78 is positioned inwardly of the pin 82. This results in forcing the toggle block 76 downwardly causing the shoulder 98 to compress the spring 96 and apply pressure to the nut 86 and bolt 68 to clamp the cutting block 64 60 to the bed. The pressure which a bolt exerts upon the cutting block can be adjusted merely by turning the bolt in its sleeve 94, thereby to lengthen or shorten the distance between the hooked portion 70 of the bolt and the pivot pin 78.

In order to provide for the support of dies and tools in proximity to the cutting block where they are used the machine is equipped with work 65 tables 100 positioned upon opposite sides of the cutting block 64. Each of the tables comprises a board 102 having on the under side thereof a metal bracket 104 which is supported by two rods 106 and 108 slidably secured to the frame 70 of the machine by set screws 110. At its forward end, the table 100 is pivotally mounted on the

rod 106 which extends through ears 112 on the bracket 104, there being a spring 114 positioned between one of the ears and a pin 116 extending through the rod whereby the table is forced toward the side of the cutting block to maintain it in juxtaposition thereto. The rearward end 5 of the table normally rests on the rod 108 without being secured thereto. The table 102 is cut away along one side thereof at 118 and at 120 to provide clearance for the clamping bolts 68 10 and for portions of the frame of the machine. When it is desired to operate the clamping bolts along the sides of the block, such bolts normally being partially covered by the tables, the tables can readily be swung about the rods 106 so that 15 they extend downwardly as shown in the right-hand portion of Fig. 5, thus to provide access to the clamping bolts. In swinging the tables to such position or in placing them back in their normal position, they may be pushed outwardly 20 of the cutting block against the pressure of the springs 114 in order to clear various of the parts of the machine during their movements into or out of normal position.

Having described my invention, what I claim as 25 new and desire to secure by Letters Patent of the United States is:

1. In a clicking machine, a bed, a cutting block supported upon the bed, a clamping member loosely carried by the bed and adapted to engage 30 the block, and a toggle member for exerting pressure upon the clamping member thereby to secure the block to the bed.

2. In a clicking machine, a bed, a cutting block positioned upon the bed, a clamping member for 35 engaging the block, and a toggle member for operating the clamping member to secure the block to the bed.

3. In a clicking machine, a bed, a cutting block supported upon the bed, and toggle mechanism 40 operative to secure the block to the bed so that the block can be readily removed from the bed.

4. In a clicking machine, a bed, a cutting block supported upon the bed, a member secured to the cutting block and having a depending portion extending through the bed, a sleeve loosely carried by the depending portion, and a lever carried by the bed for forcing the sleeve in a direction to clamp the block to the bed.

5. In a clicking machine, a bed, a cutting block 50 positioned upon the bed, a member secured to the cutting block and having a depending portion extending through the bed, and lever-operated means for engaging the depending portion to clamp the block to the bed.

6. In a clicking machine, a bed, a cutting block positioned upon the bed, means for clamping the block to the bed comprising a member engaging the cutting block and extending through the bed, a lever pivoted upon the bed and having means 60 for engaging the member to force it in a direction to clamp the block to the bed.

7. A block-securing device comprising a bolt formed to engage a portion of a cutting block, a sleeve screw-threaded on the bolt, a toggle block 65 slidably mounted upon the bolt and surrounding the sleeve, a spring positioned upon the sleeve and adapted to be engaged by a portion of the block, and a toggle lever for forcing the block in a direction to compress the spring.

8. In a clicking machine, a bed, a cutting block positioned upon the bed, a clamping device comprising a toggle lever pivotally mounted upon the bed, a clamping bolt adapted to engage a portion 70 of the cutting block and means carried by the 75

toggle member for engaging the bolt to move it in a direction to clamp the block to the bed.

5. In a clicking machine, a frame, a cutting block supported by the frame, a work table positioned adjacent to the cutting block and means for supporting the table comprising a plurality

of rods projecting laterally from the frame, a bracket on the table pivotally mounted upon one of the rods, and resilient means normally operative to force the table laterally toward the cutting block.

ROBERT N. SANDBERG.
